GEORGES DESAULLES, OF PARIS, FRANCE.

PROPELLING OR RECEIVING FLUID REACTION MACHINE ESPECIALLY APPLICABLE TO AERIAL NAVIGATION.

1,102,016.

Specification of Letters Patent. Patented June 30, 1914.

Application filed March 20, 1913. Serial No. 755,865.

To all whom it may concern:

Be it known that I, GEORGES DESAULLES, a citizen of the Confédération of Helvetia, and residing at 21 Rue Georges Sand, in the city of Paris, France, engineer, have invented a Propelling or Receiving Fluid Reaction Machine Especially Applicable to Aerial Navigation, of which the following is a full, clear, and exact description.

10 Actually most of the machines utilizing the laws of the movement and resistance of the fluids for converting mechanical work into locomotion or into displacement of fluids, often have a small output, whether 15 propelling devices, fans or motors are concerned. Especially in aerial navigation for instance, the form and means of action of the propelling devices do not answer very well to the requirement for stability and security, which is sought for.

20 The present invention has for its object a device for obtaining in the above mentioned transformations of work a better utilization and, especially in the case of aerial 25 navigation, to give to the device more powerful means of action, a greater stability and, consequently, a more extended sphere of action.

Propelling apparatus have already been 30 devised in which the active elements come, during the working or active period, in the required position so as to give the maximum useful effect and, during the inactive period, in the position which necessitates the minimum resisting stress. But in the known 35 devices, these elements are moved to their position under the controlled action of mechanical members.

In the present invention, it is the forces 40 generated by the very movement of the machine, reaction of the fluids, under the influence of the speed and centrifugal force which place the elements in their most advantageous position either for supplying 45 or generating work or for offering the minimum resistance to the movement.

In the accompanying drawings: Figures 1 to 4 are diagrammatic views serving to explain the principle of the invention; Fig. 5 shows diagrammatically in side view the present type of apparatus; Fig. 6 illustrates the same apparatus in another position; Figs. 7 to 9 show a mode of execution

of said apparatus; Figs. 7 and 8 are two cross sections showing the apparatus in two different positions; Fig. 9 is a general elevation, partly broken away.

The present type of apparatus is constructed according to the following considerations: Say a surface A^o (Fig. 1) of determined shape, for instance a curved rectangle, suspended by two of its sides and at determined points of its width $a^o a^1$, can rotate freely about these points which are connected by two rigid rods $a^o b^o a^1 b^1$ to a fixed axis $b^o b^1$.

For simplifying the demonstration, the surface or plate A^o is illustrated hereafter by its profile A, the axis of rotation $a^o a^1$ by the point a , the fixed axis $b^o b^1$ by the point b and the two rods $a^o b^o, a^1 b^1$ by the line $a b$ (Fig. 2). This plate being exposed to a stream of air of determined intensity and direction illustrated by the arrow c^1 , it will take in the space a certain setting so as to make with the direction of c^1 a determined angle α .

If instead of being held fixed, it is on the contrary supposed that the plate A is given a peculiar movement, for instance a continuous gyration about an axis b through the medium of the rod $a b$ and in the direction of the arrow g (Fig. 3), it will take of itself a setting corresponding to the minimum resistance to the reactions of the air produced by the effect of the relative speeds of the air and of the plate and the resultant of which is illustrated by the arrow h and will tend to cause rotation of the plate about the axis b .

If the plate A is accompanied by an abutment d (Fig. 4) it will be stopped in its rotary motion about its suspension axis a , at the moment when, under the effect of the reactions of the air, its setting will have brought it in contact with the abutment through the medium of the bearing member f . From this moment the plate, under the action of the effects of the relative speed of the air and of its own movement represented by the arrow h^1 , will be the seat of a thrust represented by the arrow i and which will hold it pressed against the abutment d until the direction of the movement will be such that the resistance of the air will begin to act on the back of the

plate. Being no longer held, said plate will pivot about its suspension axis a and the same cycle will be produced at each revolution the plate will make about the axis of rotation b .

The thrust due to the resistance opposed by the air to the movement of the plate stopped by the abutment is, for a form of plate suitably chosen, sensibly at right angles to the plane of the abutment and nearly constant in intensity. This thrust is transmitted by the rod a b to the axis b which becomes the seat of a traction and it may be understood that the system of which it would constitute a part and to which it would be connected, can be impelled or moved in space by this traction. The plate A will act in this case as a kind of wing, by resting or pressing upon the air with variable incidences, for producing during the active period of its displacement a traction directed in a direction determined by the position of the abutment and moving about its axis of suspension during the inactive period to such a position that it opposes to the air only the minimum resistance, these two periods succeeding alternately one another and in a continuous manner. By arranging about one and the same axis several plates having with a common movement about said axis and each provided with an adjustable abutment, a traction can be generated which is not only constant in direction but also in intensity and can be directed at will in a determined direction by the position of its abutment. This arrangement, utilizing a property of the action of the air upon movable surfaces, can serve for obtaining a propelling, driving or air displacement apparatus. Particularly, by mechanically putting into practice the cycle just described, it will be possible to produce a propelling apparatus and Fig. 5 illustrates diagrammatically, by way of example, a means of realization of an apparatus comprising six plates B, B^1 , B^2 , B^3 , B^4 , B^5 symmetrically arranged about an axis projected at C and by means of which said plates can receive a common movement of rotation while being capable of rotating themselves about their axes of suspension K , K^1 , K^2 , K^3 , K^4 , K^5 which are rigidly connected to the central axis C either by arms, or by a disk, rigidly mounted on said axis and which are not illustrated in the drawings. On the other hand, abutments I, I^1 , I^2 , I^3 , I^4 , I^5 are arranged so as to be able to rotate also about axes K to K^5 . The abutments correspond to bearing members m , m^1 , m^2 , m^3 , m^4 , m^5 secured to the plates so as to be able to press upon the abutments which are connected by trunnions n , n^1 , n^2 , n^3 , n^4 , n^5 and arms o , o^1 , o^2 , o^3 , o^4 , o^5 to central hub p . The latter rotates on a pivot q , fitted in one of the arms of member r having the shape of a

crank and which can loosely rotate on the shaft C driving the plates in its movement of rotation. The second arm of the member r is provided with a pivot s on which is mounted an operating rod t , through the medium of which it is possible to modify at will the position of the crank r and to hold it in a determined position without stopping the rotary movement of the axis C. This operation may be controlled by hand by the pilot of the apparatus either directly or through the medium of any mechanical operating device, actuated by the motor which imparts the rotary movement to the apparatus, or also by an automatic steering device. In the example chosen and for simplifying the demonstration, the setting is given integrally and simultaneously to all the abutments together, but each abutment can be provided with an independent operating device, so as to be able to give to each of the plates a certain setting at a determined point of its travel, in view of applications for which this would be recognized necessary or advantageous. The apparatus described being at rest and the crank r placed and held so as to maintain the abutments I to I^5 in the nearly horizontal position of Fig. 5, if a movement of rotation is imparted to the shaft C in the direction of the arrow u , the plates will take positions such as B, B^1 , B^2 , B^3 , B^4 , B^5 .

In the case considered, the speed of the relative displacement of the air and of the plates is directed according to the tangent to the circumference described in the space by a point of the latter. The plate B has freely set itself according to the angle which corresponds to its minimum resistance, as above set forth, under the influence of its speed, shape and weight, which may be supposed negligible relatively to the other forces to which it obeys. The plate B^1 which obeys the same law has come little by little nearer to the abutment I^1 with which it comes into contact at last when it occupies the position B^2 . From this moment its rotation about its axis of suspension ceases, but it continues to be driven by the shaft C and by reason of its setting, which now remains constant, it makes with the direction of the speed of its movement about C an angle which goes on increasing. Consequently, from the moment the plate has come into contact with the abutment, the air opposes to it a resistance which increases very rapidly and causes a pressure the resultant of which is exerted upon its axes of suspension and which remains sensibly constant and perpendicular to the direction of the abutment, that is to say, in the case under consideration, nearly vertical. This state of things lasts until the direction of the speed of the plate being then nearly horizontal, the pressure of the air will act upon its opposite face by causing it

to rock about its suspension axis and by releasing it from its abutment. This will happen at the moment the plate will occupy a position adjacent to B^5 . Said plate will 5 pivot between the positions B^5 and B and will take again the setting corresponding to its least resistance, until, in the course of its movement about the shaft C and under the command of the forces acting upon it and 10 to which it can freely obey, it will have moved toward the abutment and pressed on the same and where the cycle described will recommence.

By a judicious choice of the shape of the 15 plate, its center of gravity can be so placed that the resultant of the forces generated by the movements of the plates contributes: 1st to hold the plate pressed on its abutment during the active phase and 2d to release it 20 from its abutment and to set it in its direction of least resistance during the inactive period.

The six plates B , B^1 , B^2 , B^3 , B^4 , B^5 pass successively in these two situations alternately active and inactive, and there results therefrom a continuous traction which is transmitted to the shaft C by means of the rigid connection of the suspension axes of the plates with said shaft. In the particular 30 case under consideration, this traction is directed vertically and upwardly. Its intensity depends on the speed and on the surface of the plates in action and it may be considered as directly proportional to these 35 two factors.

The propelling device thus described being supposed placed on a system of supporting and steering planes, will take with it an ascensional movement through the effect of the 40 vertical traction directed upwardly and determined by the resistance of the air on the plates in movement. If then, and without stopping the apparatus, the operating rod t is acted upon and the crank r caused to rotate about the shaft C for bringing it in the position illustrated in Fig. 6, the abutments I and I^5 will take an inclined direction through the effect of the traction exerted upon the same through the medium of the 45 arms o to o^5 , thus determining a new setting of the plates during the active phase and, consequently, a new direction of the thrust on their axes. The whole of the system can then take, under its action, a new direction 50 in the space.

The apparatus which has just been described possesses the main following advantages:

1st. The active member, the plate, is arranged in such a manner as to be capable of placing itself, during the period of work, in such a position as to always give the maximum useful effect and to be capable, at the moment its effect becomes null, of setting 65 itself in the position which necessitates the

minimum resisting stress. The result is a very good utilization of the work.

2d. It permits giving at any moment to the force produced, the most advantageous direction in view of the effect to be obtained 70 and without sacrificing the output.

3d. It possesses inherent stability which is the consequence of its conception and mode of operation by means of plates bearing or resting on the air. Considered as an aerial 75 propelling device it will coöperate to produce general stability of any apparatus to which it will be adapted. By means of an adjusting device within reach of the pilot, it will be able to produce at will its entire 80 force for the vertical ascent, or for traveling diagonally under any angle, or for traveling horizontally; the setting of the plates can, in each particular case, be given for the obtention of the full output. It will always be possible to put in agreement the 85 direction of the stress given by the propelling device with that given by the rudders of the apparatus, which will allow more rapid evolutions and greater security. 90

4th. By coupling two devices on one and the same apparatus and by animating them with speeds in reverse direction, it will be understood that, by setting their plates so that the thrusts which are exerted upon the 95 same combat the effects of the gravity and of the wind and that the horizontal resultants be equal and of reverse direction, it is possible to hover over a spot.

The very high useful effect of the plates 100 of the propelling device will permit obtaining with a motive power even limited to the powers actually in use, an ascensional force sufficiently high for being able to rise vertically, either from the ground or from the 105 surface of the water, and to consider the lifting or carrying of heavier weights and of more powerful aerial machines than up to now. Also the landing can be effected vertically by a suitable setting of the plates of 110 the propelling device which will be able to work or operate in this case for slowing down the descent. If the apparatus is provided with two propelling devices capable if necessary of rotating in reverse direction, 115 the pilot will have still more complete control than what has been stated above.

Figs. 7 to 9 illustrate the mechanical realization of an aerial propelling device based on the preceding principles. This propelling device comprises two series of six plates B placed on the right and left of the motor. These plates may be made either of wood or of sheet aluminium or any other suitable metal or alloy. They are securely attached to the enlarged parts of the pivots a which can rotate freely in boxes b . The pivots are each provided with a cam shaped stop m which can press on the abutment I arranged inside the box. The boxes can thus rotate in rings 120 125 130

4
 c symmetrically mounted in the two plates D arranged at the right and left side of the motor M on the shaft C to which they are keyed and which imparts to them its 5 movement of rotation. Each box is provided with a crank pin n through which they are maintained in an invariable setting, during their actuation by the disks, by means of a member o having the shape of a 10 six branch star extending radially about the hub p which constitutes an eccentric strap and can loosely rotate on the disk r the latter being also loosely mounted on the shaft C.

15 The disk r is provided with an operating stud s by means of which it will be possible, through the medium of an operating device (which is not illustrated), to vary the setting of the disk and, consequently, that of 20 the boxes b and abutments I all together.

Fig. 7 is an end view of the propelling device with its abutments held horizontally. Fig. 8 illustrates the same propelling device with its abutments vertically adjusted. Fig. 25 9 is a longitudinal vertical section of the whole of the motor and of its two plates each carrying six wings and arranged one at the right side and the other at the left side of the motor. That at the left side corresponds to Fig. 7 and that at the right side to Fig. 8. Fig. 9 shows, as Figs. 7 and 8, the relative position of the pivots with the stops, the boxes with their abutments, the crank pins, the eccentric strap, and the disk 30 35 with its operating stud for the setting to be given to the plates. By examining these figures, it will be understood that it is thus possible to give to the abutments and, consequently, also to the stress produced by the 40 movement of the plates, any intermediate direction between the horizontal and the vertical and that this adjustment can be effected without stopping the motor.

By combining the steering control with 45 those of the rudders and of the warping of the wings simultaneously, it will be possible to obtain very efficient steering effects.

The motor may be mounted on a frame through the medium of a vertical trunnion 50 x allowing it to take a setting in one direction or the other. The frame may also be mounted on a horizontal axis y allowing it to take also a certain inclination.

This machine realizes in its action the 55 flight resembling that of the fly by means of a whirling of the wings similar to that produced by the wings of the insect.

Claims:

1. A propelling or receiving fluid reaction 60 machine, especially applicable to aerial navigation, comprising elements arranged in a circle, axes about which said elements can freely rotate, for causing the latter to place themselves in the working position and in 65 the position of rest, means for actuating the

elements in a continuous gyral motion about the center of the said circle, and adjustable abutments for stopping the active elements in a given position so that the air opposes to these elements a resistance creating a 70 thrust tending to move the machine in a determined direction.

2. A propelling or receiving fluid reaction machine, especially applicable to aerial navigation, comprising plates arranged in 75 a circle, axes about which said plates can freely rotate for causing the latter to place themselves freely in the working position or in the position of rest under the action of the reactions of the air and of the speed of 80 the machine, means for actuating the plates in a continuous gyral motion about the center of the said circle, abutments for stopping the active plates in a given position, and means for adjusting the position of the 85 abutments without stopping the gyration of the plates.

3. A propelling or receiving fluid reaction machine, especially applicable to aerial navigation, comprising plates arranged in 90 a circle, axes about which said plates can freely rotate for causing the latter to place themselves freely in the working position or in the position of rest under the action of the reactions of the air and of the speed of 95 the machine, means for actuating the plates in a continuous gyral motion about the center of the said circle, abutments hinged on the axis of the plates for stopping the latter in a determined position, means for connecting all these abutments to a common axis eccentric relatively to the gyration axis, and other means for displacing the axis of the abutments.

4. A propelling or receiving fluid reaction machine, especially applicable to aerial navigation, comprising plates arranged in a circle, movable axes for the plates, movable boxes receiving said axes, disks, sleeves carried by the disks and receiving said boxes, a 105 shaft on which are secured the said disks, abutments for stopping the active plates in a given position, and means for adjusting the position of the abutments without stopping the gyral motion of the plates.

5. A propelling or receiving fluid reaction machine, especially applicable to aerial navigation, comprising plates arranged in a circle, movable axes for the plates, movable boxes receiving said axes, a crank pin 110 integral with each box, disks, sleeves carried by the disks and in which the boxes can rotate, a central shaft on which are mounted the disks, a motor for actuating said shaft, abutments for stopping the active plates in 115 a given position, and means for adjusting the position of the abutments without stopping the gyral motion of the plates.

6. A propelling or receiving fluid reaction machine, especially applicable to aerial 120

- navigation, comprising plates arranged in a circle, movable axes for the plates, a boss longitudinally arranged on each axis, movable boxes receiving said axes, an abutment for the boss of the axis, arranged within each box, a crank integral with the latter, disks, sleeves in which can rotate the boxes carried by the disks, a central shaft on which are mounted said disks, an eccentric capable of loosely rotating on said shaft, a strap surrounding said eccentric, arms integral with said strap, connected at their end with the crank pins of the boxes receiving the axes of the plates, and means for rotating the eccentric.
7. A propelling or receiving fluid reaction machine, especially applicable to aerial navigation, comprising plates arranged in a circle, movable axes for the plates, a boss longitudinally arranged on each axis, movable boxes receiving said axes, an abutment for the boss of the axis, arranged within each box, a crank integral with the latter, disks, sleeves in which can rotate the boxes carried by the disks, a central shaft, on which are mounted said disks, an eccentric capable of loosely rotating on said shaft, a strap surrounding said eccentric, arms integral with said strap, connected at their end with the crank pins of the boxes receiving the axes of the plates, a stud mounted on the eccentric and connected to an operating device for rotating the eccentric and modifying the position of the abutments of the boxes.
8. A propelling or receiving fluid reaction machine, especially applicable to aerial navigation, comprising a motor, a shaft actuated by said motor, metal disks, one placed on each side of the motor, sleeves integral with said disks, boxes capable of rotating in said sleeves and each provided with an inner abutment and an outer crank, an axis provided with a boss fitted in each box, a plate carried by said axis, an eccentric capable of loosely rotating on the central shaft at each side of the motor, a strap surrounding said eccentric, arms integral with said strap and connected to the crank pins of the boxes receiving the axes of the hinged plates, means for modifying the position of the abutments of the box, a joint for causing the machine to rotate on itself and another joint for laterally inclining the machine.
- The foregoing specification of my propelling or receiving fluid reaction machine, especially applicable to aerial navigation, signed by me this seventh day of March, 1913.
